UNITED STATES PATENT OFFICE.

THOMAS LAWSON, OF NEW YORK, N. Y.

DUMPING-CAR.

SPECIFICATION forming part of Letters Patent No. 682,206, dated September 10, 1901.

Application filed December 14, 1900. Serial No. 39,873. (No model.)

To all whom it may concern:

Be it known that I, THOMAS LAWSON, a citizen of the United States, residing in the borough of Manhattan, in the city and State of New York, have invented a certain new and useful Improvement in Dumping-Cars, of which the following is a specification.

The improved cars may be made of various lengths and with any required number of wheels. I will describe the invention as applied to a relatively short dumping-car with four wheels.

The material to be transported and dumped, which I will for brevity term "earth," is held in two movable bins or carriers of dimensions suitable for occupying each the breadth from the center line to one of the sides of the car. I provide for moving these outward either singly or simultaneously and for tilting each carrier suddenly after it has been moved into its extreme outboard position.

I provide the car with transverse rails and equip each carrier with a series of balls serving as antifriction devices, the balls in one portion of their course carrying the load imposed through the carrier and in the return portion of their course running light. I mount and properly guide and retain these series of balls on the under sides of the carriers and provide the car simply with transverse rails, allowing the balls to run thereon during the main part of the loaded portion of their respective courses. During most of the several movements the weight is carried on the balls. During the act of dumping it is slightly raised and supported on journals.

I have invented important improvements in the mechanism for the storing and application of power. I employ nearly horizontal oscillating cylinders containing pistons operated by compressed air with facilities for effecting the required bodily movements and the tilting of each carrier and for perfectly controlling and gently arresting each movement.

The following is a description of what I consider the best means of carrying out the invention.

The accompanying drawings form a part of this specification.

Figure 1 is an end view in elevation with one of the carriers in the position in which it is loaded and transported and the other, the left, in the act of being dumped. Fig. 2 is a corresponding plan view. Fig. 2^a is a longitudinal section of a portion corresponding to Fig. 2, showing the recesses in the compressed-air vessels in their relation to the bearing-axles. Fig. 3 is a central vertical section, on a larger scale, showing one of the carriers, that on the left side, in its inboard, and consequently horizontal, position. Fig. 4 is a section on the inclined line 4-4 in Fig. 1. Fig. 5 shows a portion, on a larger scale, corresponding to the right side in Fig. 1. Fig. 6 is a vertical cross-section on the line 6-6 in Fig. 3. Fig. 7 is a side elevation of a portion showing a modification.

The figures show the novel parts, with so much of the ordinary parts as is necessary to indicate their relation thereto.

Similar letters of reference indicate corresponding parts in all the figures where they appear.

A is the body of the car; A', the bearings of the axles; D, the axles, and D' the wheels. There may be any ordinary or suitable provisions for elastic action by springs. (Not shown.)

B B are two equal carriers extending lengthwise of the car on each side and capable of being moved outward bodily and arranged to also tilt when at the extreme outboard position. Each is supported on two transverse ways composed of narrow rails A², stiffly supported on the floor of the car-body A, on which run a series of balls C, carried in a casing or way B', extending transversely of the carrier and having curved ends B² connecting this way with another nearly similar one, B³. The carrier is supported on the balls C, which rest on the rails A² as they are moved outward or inward, the balls accommodating the motion and traveling through the curved portions B² at each end and returning idly in the channel B³. This return-channel may completely inclose the balls; so may a portion of each of the curved parts B². The portion B', in which the balls are effective at any given moment, is strong and equipped

to present a smooth continuous bearing on the upper side of its interior and has a longitudinal aperture b , extending its whole length on the lower side, into which the rail A^2 is received. Each carrier during the first part of its outward motion travels horizontally. Near the outer end of its traverse it is raised off the ball-bearings by means of inclines A^3 and supported on journals B^4 , which are strongly attached to the ends of each carrier by brackets B^5 , which extend downward a little, as will presently appear. These journals, with small antifriction-wheels carried thereon, are received in stout hooks A^4 , set on the body A . In this condition the carrier is free to tilt on the journals, and I so proportion the weight and so arrange the impelling force that it is certain to tilt when moved out actively, and thus slightly elevated by the inclines and arrested by the hook-bearings. After either carrier has been thus moved outward and tilted and has dumped its load I apply the nearly horizontal force in the reverse direction. This first restores the carrier promptly to its horizontal position and then moves it bodily inward again down the slight incline and along its ball-bearing path to its original place, ready to receive in due course another load, and so on.

E' represents self-acting dogs, one at each end, turning each on a pivot A^5 and subject to a gentle spring E^2 , which when free raises it to the position shown in Fig. 6. A cord E^3 , connected near the free end of each, runs under a guide-pulley E^4 and extends to the end of the car subject to the action of the operator. When a carrier is drawn inward after each dumping action, its wheels E roll over the dogs E' and depress them. So soon as the carrier has passed to its extreme inward position, bringing the wheel E against the fixed chock A^6 , each dog E' rises and holds the wheel, and consequently the carrier, against moving outward until the operator has again depressed the dogs. The two cords by which the two dogs are pulled down previous to the dumping action may both lead to the same point at the end of the car, and there may be provisions for belaying the cord, thus relieving the attendant from holding it while he operates the dumping means.

I provide means for applying force to effect the movements of each carrier at each end simultaneously and equally, attaining this by oscillating cylinders and pistons. I have discovered that it is practicable to allow the required long range of motion and to apply the force so as to effect both the bodily and dumping movements with the required promptness and certainty, and also to effect a cushioning of the pistons, so that the carrier will be arrested gently and without shock at each end of the motion. I attain these ends with economy of space by mounting the operating-cylinders under the carriers and providing connections which are recessed by the

aid of means, which we may term "boxes," provided in the base and inner side of the carrier.

G , G' , &c., are the oscillating cylinders, arranged in pairs and connected each to operate one end of the opposite carrier. All four may be substantially alike and a description of one will suffice for all.

W is a piston, and W' a piston-rod engaged by a T-shaped end W^2 , with bearings carefully located and protected in the opposite carrier.

Each cylinder G turns on hollow trunnions G' , G^2 , strongly supported on the car and equipped with proper stuffing-boxes F' , F^2 . The trunnion G' connects with the outer end of the cylinder adjacent to the trunnion. H , h is a three-way cock, which in one position, that shown in Fig. 4, connects this trunnion G^2 by means of the passage H' with the pipe K , which is kept supplied with compressed air, and in the opposite position allows compressed air previously in the outer end of the cylinder to escape through the pipe H^2 into the atmosphere. The other trunnion G^2 is longer and connects through a passage G^3 with the inner end of the cylinder G . This controls the pressure on the opposite (the inner) face of the piston. This passage cast in the exterior of the cylinder connects through the three-way cock I , in one position of such cock, with the interior of the cylinder, and thus communicates through the trunnion G^2 with the same compressed-air supply K . In another position of this cock I the compressed air in the inner end of the cylinder G will be allowed to exhaust through the passage G^3 , the trunnion G^2 , and the three-way cock I into the atmosphere. The cocks H , h and I are connected by a rod M and the levers H^3 , I^3 , so that the attendant by moving the rod M will operate both cocks. In the mid-position of the cocks the compressed air will be excluded entirely from each end. This is the ordinary condition of rest. When the rod M is moved to one side—the left, as shown in Fig. 4—the cock H , h admits the air through the trunnion G' and rapidly forces the piston out to effect the dumping movement. When it has moved some portion of the distance, determined by practice, and it with the connected carrier is moving rapidly outward, the operator shifts the bar M first into the middle position, arresting any further consumption of the compressed air and allowing that already received to act expansively. As it nears the end of its outward movement, the air before it—that in the inner end of the cylinder—being cushioned serves as a means of rapidly and gently arresting the outward movement, so that the journals B^4 are received in the hooks A^4 without injurious concussion. I arrange the journals as low as is practicable and set the inclines and hooks correspondingly low in order that the tilting motion of the carrier in effecting the dump-

ing will project the carrier well outboard. At any time after the dumping, which will under ordinary conditions be immediately, the operator must shift the rod M to the other 5 extreme of its motion, the right in Fig. 4. This will allow the compressed air to escape through H h and to flow from the pipe K inward through the trunnion G², passage G³, and cock I i, entering the inner end of the 10 cylinder G, and pressing on the inner face of the piston W repeats the same operation in the opposite direction. In this inward movement the carrier is light and will be first restored to its horizontal position and then 15 drawn inward. The cutting off of the compressed air may be effected earlier in this inward movement. The cushioning to arrest this inward movement may be reinforced, if necessary, by a momentary shifting of the 20 rod M and its connections to admit compressed air in front of the piston. On the other hand, if the cushioning should arrest the inward motion too early the inward impelling force may be similarly reinforced by 25 shifting the rod M briefly to the right.

I attach importance to the driving of the carrier outward with rapidity and decision at sufficient velocity to insure that the journals B⁴ shall travel up the inclines A³ and be 30 arrested gently in the hooks A⁴ without any chance of failure. At this stage the carrier is loaded and is in its extreme outboard position; but the case is different with regard to the inward motion, the carrier being then 35 light and near its central position on the car.

I supply a loose-fitting ring E on each of the journals B⁴, which turns and serves as an antifriction bearing-wheel when the carrier is supported thereby on the inclines A³.

40 The air-supply in the pipe K is maintained from a pump on the locomotive. (Not shown.) The pump may be the same which is ordinarily used for operating a brake system. It connects through a pipe L and a check-valve 45 L' with a connected series of strong vessels L², extending longitudinally of the car and properly recessed at the points L³, so that they do not touch the axles D. (See Fig. 2^a.) The pipes K connect at convenient points 50 with the capacious reservoir of compressed air provided by this series of vessels K² on the same car.

I provide for operating the rods M simultaneously and equally for both cylinders on 55 one side, and doing this from a convenient position at the end of the car.

P' is a sufficiently strong cord branched and attached to the respective pivots M' at the mid-length of each rod M on one side of the 60 car. The cord leads around a guide-pulley N', thence to an easily-accessible point at the end of the car, where it is equipped with a suitable handle. P² is another cord similarly branched and connected to the pivots 65 M' and leading around a guide-pulley N² and thence to the same end of the car. The op-

erator, seizing the two handles in his two hands, can by pulling on either cord P' or P² and relaxing the tension on the other operate the valves from the end of the car. There 70 may be a similar provision for operating from the other end of the car, if desired.

It will be understood that there are tight cocks on the pipes L and provisions for connecting and disconnecting the cars, so that 75 different cars may be coupled to each other and to the locomotive, as may be required or preferred in different cases.

I have shown the end of the piston-rod as equipped with a T-head forged thereon, which 80 rocks in two brackets strongly set on each side of the recess in the base of the carrier, which allows the piston-rod to play.

I employ binders secured by bolts, as usual.

The device may have any ordinary or suitable provisions for oiling. 85

B⁶ is the removable box, and B⁷ designates the screws which confine it. To get access to the pivot, the fastenings B⁷ and box B⁶ are removed, and then the binder and its fastenings may be treated in the ordinary manner. 90

There have been many efforts to utilize compressed air in operating the mechanism of dumping-cars. Mine is superior to any known to me in acting directly to not only 95 dump the carriers, but also to move them bodily outward and inward. My invention also allows either side to be dumped separately, as is required under some conditions, as in dumping from a temporary track along 100 one edge of a previously-filled area of ground. The construction stores great quantities of compressed air on each car in close connection with the cylinders and allows the power available for compressing the air to be utilized 105 for long periods continuously at a moderate rate instead of violently at long intervals or of providing an extraordinary and inconvenient air-reservoir on the locomotive, as would be otherwise necessary. It will be 110 seen that the storage of compressed air in such connected cylinders L may serve for a dumping motion or a return motion, or both, after the car has by momentum or other force 115 been allowed to separate entirely from the locomotive.

Modifications may be made without departing from the principle or sacrificing the advantages of the invention.

I can provide a separate engine and boiler 120 on one of the cars to operate the pump for compressing air instead of utilizing the power of the locomotive.

Parts of the invention can be used without others. 125

Two pairs of cylinders, one near each end of the car, are essential if the car and the carriers are long; but when short one pair of cylinders located at the mid-length of the car may serve well.

130 I can employ other means than the series of ball-bearings to allow the easy movement

of the loaded carrier outward and the subsequent return in the light condition along the level way. The inclines A lifting the carrier slightly as it approaches the termination of its outward movement takes it off the balls previous to the tilting motion and continues to hold the journals until the carrier has been drawn back to its horizontal position and moved a little inward. This is of advantage; but I can operate with some success by omitting these inclines and making the hooks and corresponding portions level, not lifting the carrier so as to be of much effect. Fig. 7 shows such modification.

15 I use the term "inclines" in this paper to mean the portions of the hook-supports adjacent to the hooks which receive the weight of the carrier and its load through the rings or small wheels E and journals B⁴, the portions which carry the load in the act of transmission from being supported on the ball-bearings to being supported in the hooks.

15 The hook form of the bearing for the tilting is important in resisting the tendency which may be experienced from the gravity of the tilted load or from a too powerful thrust in the cylinder, or both these forces, to throw the journals out beyond their proper bearings.

30 I consider it a portion of the invention if only one carrier should be used. In such case the carrier can be made somewhat wider; but in other respects the mechanism may be the same as one-half of this shown.

35 Two of the continuous series of ball-bearings, one at each end, are necessary. A third, at the mid-length, can be used, if preferred, when the car is very long. It is not necessary to represent such third series. It 40 may be identical in every respect with one of those shown.

I claim as my invention—

1. In a dumping-car, having two continuous series of ball-bearings to provide easy movements of loads transversely of the car, a carrier adapted to run thereon from inboard to outboard positions and return, two inclines and hooks at the outboard end of the traverse, journals on said carrier arranged to be received in such hooks and allow the carrier to be tilted to dump a nearly horizontal cylinder carrying a piston and connections arranged to give both the horizontal traversing and the tilting motion, and means controllable at will for supplying compressed air to act on such piston in opposite directions to induce the movements to traverse horizontally and dump and return, combined substantially as herein specified.

60 2. In a dumping-car, having two continuous series of ball-bearings to provide easy movements of loads transversely of the car, two carriers adapted to run thereon from inboard to outboard positions and return, two inclines and hooks at the outboard end of the traverse on each side, two journals on each carrier ar-

1 ranged to be received in such hooks and allow the carrier to be tilted to dump a nearly horizontal cylinder for each carrying a piston and connections arranged to give both the horizontal traversing and the tilting motions to each carrier, and means controllable at will for supplying compressed air to act independently on each such piston in opposite directions to induce the movements to traverse horizontally and dump and return simultaneously or either alone, all combined substantially as herein specified.

3. In a dumping-car, having two continuous series of ball-bearings to provide easy movements of loads transversely of the car, a carrier adapted to run thereon from inboard to outboard positions and return, two inclines and hooks at the outboard end of the traverse, journals on said carrier arranged to be received in such hooks and allow the carrier to be tilted to dump a nearly horizontal cylinder carrying a piston and connections arranged to give both the horizontal traversing and tilting motions, and means controllable at will for applying compressed air to act on such piston in opposite directions to induce the movements to traverse horizontally and dump and return, such means comprising operative cocks H and I, one for each end of each cylinder, the levers H³ and I³ and the rod M connecting them and means for operating the rod from the end of the car so as to not only effect the admission of the compressed air to drive the carrier in either direction but also to effect the cutting off of the impelling-air and the cushioning of the air in advance of the piston by simple movements, all substantially as herein specified.

4. In a dumping-car, having two continuous series of ball-bearings to provide easy movements of loads transversely of the car, a carrier adapted to run thereon from inboard to outboard positions and return, two inclines and hooks at the outboard end of the traverse, journals on said carriers arranged to be received in such hooks and allow the carrier to be tilted to dump a nearly horizontal cylinder carrying a piston and connections arranged to give both the horizontal traversing and tilting motions, and means controllable at will for applying compressed air to act on such piston in opposite directions to induce the movements to traverse horizontally and dump and return, the removable box B⁶ in such carrier allowing the pin B⁴ to be set high and the application of the force in inclined directions and also allowing easy access to such pin, all substantially as herein specified.

5. In a dumping-car, having a carrier adapted to run easily from inboard to outboard positions and return, two inclines and hooks at the outboard end of the traverse, journals on said carrier arranged to be received in such hooks and allow the carrier to be tilted to dump, a nearly horizontal cylinder carrying a piston and connections arranged to give

both the horizontal traversing and the tilting motions, means controllable at will for applying compressed air to act on such piston in opposite directions to induce the movements, 5 and the strong and light reservoir L² for storing compressed air on the car, all combined substantially as herein specified.

In testimony that I claim the invention above set forth I affix my signature in presence of two witnesses.

THOMAS LAWSON.
